UNITED STATES PATENT OFFICE.

JAMES N. HEALD, OF WORCESTER, MASSACHUSETTS, ASSIGNOR TO THE HEALD MANUFACTURING COMPANY, OF WORCESTER, MASSACHUSETTS, A CORPORATION OF MASSACHUSETTS.

FEED MECHANISM FOR AUTOMATIC GRINDING MACHINES.

Application filed April 7, 1923. Serial No. 550,420.

To all whom it may concern:

Be it known that I, JAMES N. HEALD, a citizen of the United States, residing at Worcester, in the county of Worcester and Commonwealth of Massachusetts, have invented a new and useful Improvement in Feed Mechanism for Automatic Grinding Machines, of which the following, together with the accompanying drawings, is a specification.

The present invention relates to automatic grinding machines, wherein the pieces of work to be operated upon are presented successively, by mechanical means, to the grinding wheel. The invention is here shown as a mechanism for the automatic handling of small flat articles, such as piston rings, or the like, which are successively moved into and out of grinding position,—being subject, while in grinding position to rotation, by the corresponding movement of a magnetic chuck or other holding means.

The invention contemplates improvements in mechanism of this class, by way of adapting it readily to various diameters and thicknesses of work, in connection with which, more particularly, the invention resides in a novel form of work magazine, and also a novel form of work carrier, both of these parts accommodating themselves to variations over a wide range in the character of the work. Other and further features and advantages of the mechanism forming the subject of the present invention will be apparent as the description thereof proceeds, reference being had to the accompanying drawings, in which—

Fig. 1 is a top plan view of the improved feed mechanism, shown in operative relation to the grinding wheel and rotating magnetic chuck of an automatic grinding machine.

Fig. 2 is a view, partly in section and partly in elevation, of the mechanism shown in Fig. 1.

Fig. 3 is a plan view of the work carrier.

Fig. 4 is a plan view, on an enlarged scale, of one of the removable interchangeable retainer rings, used with said work carrier.

Figs. 5 and 6 are sectional views, taken respectively on the lines 5—5 and 6—6 of Fig. 3.

Fig. 7 is a sectional view, taken on line 7—7 of Fig. 4.

Like reference characters refer to like parts in the different figures.

Referring first to Figs. 1 and 2, the numeral 1 indicates the stationary work supporting table of an automatic grinding machine, the latter being preferably of the general type disclosed in United States Letters Patent to Littman, No. 1,361,883, dated December 14, 1920. The construction and operation of such a machine, aside from the work feeding mechanism herein described and claimed, forms no part of the present invention, and hence is neither shown nor described in this application. For the purpose hereof, it is sufficient to note that in conjunction with the table 1, the machine provides a rotating work holding magnetic chuck 2, whose surface is flush with that of the table, and that the successive disposition of individual pieces of work upon said chuck, by movement across said table, procures the action on said pieces of an overhanging grinding wheel 3, indicated by broken lines in Fig. 1.

The table 1 is of generally circular formation, and for the movement of the pieces of work on the surface thereof, the invention provides a movable work carrier in the form of a thin disk 4, concentric with the table 1 and in contact with the supporting surface of said table. According to the invention, the articles to be ground, of uniform size, are held in the form of a vertical stack, within a magazine designated generally by the numeral 5, the lowermost article of the stack resting by gravity flat against the feeding disk 4, as hereinafter more fully described. In order to permit movement of the disk 4 without any interference from the magazine 5, the latter has

its support in a skeleton member 6, which is spaced above the table 1 and disk 4, being secured to the central post 7 of said table and to other posts 8, 8, projecting upwardly from the edge of said table beyond the periphery of disk 4.

Rising vertically from the stationary member 6 are the fixed posts 9, 9, arranged in a circular series and equally spaced. Each of these posts serves as the support for an

elongated vertical plate 10, said plates 10 cooperating to confine the articles in stack form. To this end, each plate 10, at an intermediate portion, has one or more supporting brackets 11, 11, by which it is adjustably carried on its associated post 9; as shown, this means of support permits vertical adjustment of each plate 10 and also adjustment about the axis of its associated post 9, since the brackets 11, encircling said posts, are adapted to be clamped in any position desired by means of bolts 12. In this way, as regards the diameter of the articles to be held in stack formation, the plates 10, cooperate to form an adjustable confining means, with their inner flat faces lying substantially tangent to the peripheries of the articles for the entire height of the stack. Furthermore, as regards the thickness of such articles, the plates 10, projecting downwardly through the skeleton member 6, afford, by their susceptibility to vertical adjustment on the posts 9, the necessary latitude in connection with the successive withdrawals from the magazine, by the action of carrier disk 4, as will now be described.

The carrier disk 4, secured to hub member 13, which is journaled on the central post 7, is subject to intermittent movement in a counterclockwise direction, according to the means disclosed in the copending application of Heald and Guild, Serial No. 476,496, filed June 10, 1921. To this end, an arm 14, adapted to swing on the post 7, has its outer end connected to a rod 15, which, by its connection to a crank, not shown, procures the oscillation or vibration of arm 14 through a limited arc. Said arm 14 carries a pivoted pawl 16, adapted to engage with suitable notches 17 in the periphery of hub 13. It will be clearly understood that each counter-clockwise movement of arm 14, corresponding to one-half a revolution of its driving crank, not shown, procures one step in the advancement of the carrier disk 4; but that on each reverse movement of the arm 14, the pawl 16 is inoperative, the carrier disk 4 being held stationary, as described in the Heald and Guild application, by a spring pressed member 18, whose wedge shaped point enters successive depressions 19 on the periphery of hub 13.

The carrier disk 4, as shown in Fig. 3, provides a circular series of apertures 20, 20, here shown as five in number, corresponding to the five steps or intermittent movements of said carrier disk in making one complete revolution. These apertures 20 are adapted to receive retaining rings of the general form shown at 21 in Figs. 4 and 7, such retaining rings being provided in a plurality of sets, all of the same outside diameter, to fit the apertures 20, but 65 of different inside diameters, to accommo-

date them to various sizes of work. In other words, the holes 22, in which the pieces of work are received, will be of one diameter in one set of rings 21 and of another diameter in another set of rings 21, so that for a given size of work to be ground, the proper set of retaining rings 21 can be selected and inserted in the apertures 20 of the carrier disk 4.

For the retention of the rings 21 in disk 4, the construction of the apertures 20 is, as shown in Figs. 3, 5 and 6, to provide a seat 23 for the support of each ring, with its upper surface flush with the upper surface of the disk 4. As shown in Fig. 6, 80 the aperture 20, above the seat 23, provides an annular undercut shoulder 24, and in the process of manufacture, portions of the material of this shoulder are cut away, as shown at 25, Fig. 5, to accommodate correspondingly spaced bevelled enlargements 26 on the circumference of each ring 21. This construction permits insertion of a ring 21 by registration of the parts 25 and 26; thereupon, the ring is turned through a suitable angle so as to dispose its bevelled projections 26 below the undercut shoulder portions 24, thus locking the ring against displacement, but permitting its ready removal when desired, simply by giving it the requisite partial rotation in the aperture 20. When all of the rings 21 are in place, as shown in Fig. 1, they may be secured against accidental turning movement by the engagement therewith of an annular plate 27, 100 which encircles the hub portion 13 of the carrier disk 4.

In the operation of the mechanism, assuming the provision of the proper sized rings for the work that is stacked up in the magazine 5, it will be seen that each intermittent movement of the carrier disk brings one of its apertures 20 directly below and into concentric relation to the stack of piston rings, washers, or the like, to be ground. 105 During each such movement, the stack rests by gravity on the disk 4, the lowermost piece of said stack being in contact with the surface of said disk, but prevented from moving therewith by its confinement by the lower ends of plates 10, 10. As soon as one of the holes 22, of predetermined proper size, comes to rest, in registry with said lowermost article, the latter drops into said hole, and rests against the surface of table 1. Thereupon, on the next movement of the carrier disk 4, said article is carried along with said disk, but the article next above, confined by the plates 10, is held at the bottom of the stack, and lies in contact 115 with the surface of the moving disk 4. It will be understood that the proper vertical adjustment of the plates 10 insures the release of an article upon its descent through a hole 22 into contact with the table 1, but 120 125 130

insures the retention of an article so long as it rests on the surface of the disk 4.

The article thus removed from the bottom of the stack is conveyed by the disk into position for grinding, as indicated at A, Fig.

1. In this position, the article rests on the surface of the rotating magnetic chuck 2, and in consequence of its rotation, all parts of its surface are subject to the action of the

10 grinding wheel 3, as will be well understood by those conversant with machines of this character. Upon the completion of the grinding operation, the withdrawal of the wheel 3 effects automatically another move-

15 ment of the carrier disk 4, which conveys the article across the face of table 1 to the position indicated at B, Fig. 1, at the same time bringing another article into grinding position, as will be well under-

20 stood. The next ensuing movement of the carrier disk 4 advances each of the several articles one step, bringing the first article into registry with an aperture 28 in the table 1 of larger diameter than said article, where-

25 by the latter drops through by gravity onto an inclined grating 29 and is discharged from the machine, as indicated at C, Fig. 1. In this way, the ring 21, which had previously served for the movement of said

30 article, becomes available for the removal of another article from the bottom of the stack, this being accomplished upon its travel from the position D to the first de- scribed position of registration with said

35 stack.

It is to be noted that when an article is in grinding position A, its retaining ring 21 is prevented from being frictionally rotated, by the above described plate 27, the latter having suitable pins 30 which enter into corresponding holes 31 in the edge of each ring. Also, in this grinding position, the article is prevented from being accidentally displaced by an overlying shield 32 which is carried upon a post 33 projecting downwardly from the member 6.

I claim,

1. In a work feeding mechanism for automatic grinding machines, a magazine comprising a circular series of rigid supports, and an elongated stack confining member adjustably carried by each support for tangential contact with the work.

2. In a work feeding mechanism for automatic grinding machines, a magazine comprising a series of rigid supports, and an

elongated stack confining member carried by each support and angularly adjustable about the axis thereof.

3. In a work feeding mechanism for automatic grinding machines, a magazine comprising a circular series of rigid supports, and an elongated stack confining member, for tangential contact with the work, carried by each support and vertically adjust- 60 able thereon.

4. In a work feeding mechanism for automatic grinding machines, a magazine comprising a series of rigid supports, and an elongated stack confining member carried 70 by each support and adjustable angularly and vertically with relation thereto.

5. A magazine adapted to confine circular articles in stack formation, comprising a series of members each adapted for angular 75 adjustment, whereby to accommodate articles of different diameters, and each pre- senting inwardly an extended flat surface, whereby to insure tangential contact with stacks of various sizes. 80

6. In a work feeding mechanism for automatic grinding machines, the combination with an apertured carrier, of retaining rings 85 for the work, insertible in the apertures of said carrier, and a common locking means for holding all of said retaining rings against displacement.

7. In a work feeding mechanism for automatic grinding machines, the combination with an apertured carrier, of retaining rings 90 for the work, insertible in the apertures of said carrier, and adapted to be locked therein by a turning movement.

8. In a work feeding mechanism for automatic grinding machines, the combination 95 with an apertured carrier, of retaining rings for the work, insertible in the apertures of said carrier, the wall of each aperture pro- viding an undercut portion, and each ring having a projection adapted to engage said 100 undercut portion, when the ring, after inser- tion in the aperture, is turned.

9. In a work feeding mechanism for automatic grinding machines, the combination with an apertured carrier, of retaining rings 105 for the work, insertible in the apertures of said carrier and adapted to be locked there- in by turning movement, and means, com- mon to all of said rings, for preventing un- locking movement thereof. 110

Dated this 31st day of March, 1922.

JAMES N. HEALD.
